UNITED STATES PATENT OFFICE.

LEON NOVAK, OF NEW YORK, N. Y.

SCRAPING TOOL.

1,412,883.

Specification of Letters Patent. Patented Apr. 18, 1922.

Application filed February 7, 1920, Serial No. 356,939. Renewed March 7, 1922. Serial No. 541,345.

To all whom it may concern:

Be it known that I, LEON NOVAK, a citizen of Poland, residing at 548 East 147th St., New York city, in the county of Bronx and State of New York, have invented certain new and useful Improvements in Scraping Tools; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates generally to improvements in floor and veneer scraping tools; and the invention has reference, more particularly, to an improved construction of means for rigidly securing the scraping blade in assembled relation to the tool.

The invention has for its principal object to provide in combination with scraping tools a novel construction of blade holder and locking device whereby the blade is securely and rigidly held in operative relation to the tool, and in a manner eliminating all tendency of the blade to slip or to vibrate, thereby overcoming all tendency of the blade to chatter when the tool is used, and consequently eliminating "checking" of the surface scraped by the blade. By "checking" I mean the production of wavy gouges in the scraped surface, rather than the perfectly smooth level surface desired to be produced by the tool.

Other objects of the present invention, not at this time more particularly enumerated, will be clearly understood from the following detailed description of the same.

With the various objects of the present invention in view, the same consists, primarily, in the novel blade holding means for scraping tools hereinafter set forth; and, the invention consists, furthermore, in the novel arrangements and combinations of the various devices and parts, as well as in the details of the construction of the same, all of which will be hereinafter more fully described, and then finally embodied in the claims appended thereto.

The invention is clearly illustrated in the accompanying drawings, in which:

Figure 1 is a top plan of a floor and veneer scraping tool provided with the novel blade holding means made according to and embodying the principles of my present inven-

tion; Figure 2 is a vertical longitudinal section through the same, taken on line 2—2 in said Figure 1; Figure 3 is a detail vertical longitudinal section through the blade holding means drawn on an enlarged scale and with the clamp-plate slightly released to show the initial concavity of the inner binding surface of the same; and Figure 4 is a detail transverse section, taken on line 4—4 in said Figure 3.

Similar characters of reference are employed in all of the hereinabove described views, to indicate corresponding parts.

Referring now to said drawings, the reference-character 1 indicates the base of the scraping tool having the usual laterally disposed opening 2, through which the blade is projected to working position, and also having the usual side flanges 3 projecting upwardly from its longitudinal edges. Said side flanges 3 are provided with the vertically disposed re-enforcing portions 4, upon the upper ends of which, and to which is secured by fastening screws 5, or otherwise, the transverse hand-grip bar 6, having at its free ends the oppositely and outwardly projecting handle portions 7.

Transversely disposed between said side flanges 3, and above said opening 2 of the base 1, is a blade holding frame, the same comprising a back plate 8, having at its lower margin a re-enforcing transverse rib 9 provided in its opposite ends with sockets 10. Connected with said respective side flanges 3 are inwardly projecting fulcrum pins 11, which respectively enter said sockets 10, thereby serving to pivot said blade holding frame so that the same may be swung forwardly or rearwardly to adjust the blade.

100 To be held in said frame to the desired angle or pitch. The means for adjusting the frame for such purpose comprises the threaded link-rod 12, one end of which is pivoted to and between ears or lugs 13 projecting rearwardly from the back face of said back plate 8. The free end of said link-rod 12 extends rearwardly through the perforation 14 of an anchor post 15, connected with the rearward end of said base 105

1. A rearward lock nut 16 threaded on said link-rod to engage one side of said anchor post, and a forward lock nut 17 also threaded on said link-rod to engage the other side of said anchor post may be manipulated in the customary manner to effect the desired adjustment of said blade hold-

ing frame, and then to lock the same in the adjusted position so effected.

Intermediate the upper and lower ends of said back plate 8 is a transverse front bar

- 5 18, integrally connected with the side portions of said back plate and forwardly offset therefrom by means of end members 19 to provide an intermediate opening or slot 20. Extending through said opening or slot 10 20, in the front of said back plate 8 is a clamp-plate 21. Said clamp-plate 21 is provided in its side margins with notches 22 which engage over supporting pins 23, the latter being anchored in said end members 15 19 to project inwardly into the slot 20. Said supporting pins 23 as engaged by the notches 22 of said clamp-plate 21, serve to retain the latter in operative relation to the blade holding frame, and also serve to guide the clamp-plate 20 in bodily forward or rearward movement or play within said slot 20. Connected with the lower edge of said clamp-plate is a transverse guard rib 24, the under side 25 of which is upwardly and forwardly chamfered. Said guard rib projects beyond the boundaries of said slot 20 and guards the same against the entrance thereinto of shavings, dirt, etc., when the tool is in use, the chamfered under side of said rib serving to 25 30 turn forward and away from the blade holding frame the shavings passing upwardly through said openings 2 of the base 1 when the tool is operated.

The reference-character 26 indicates a

- 35 scraping blade, the same, when properly assembled in the blade holding frame, being disposed between said back plate 8 and said clamp-plate 21, so that its lower working or cutting edge projects downwardly 40 through the opening 2 of the base 1 to the desired extent. When the blade 26 is properly positioned, the clamp-plate 21 is forced rearward bodily, to press against the face of the blade, and to force the rear face of 45 the same firmly against the back plate 8. The means for so moving the clamp-plate 21 comprises a set screw, the shank 27 of which is threaded through the front bar 18 so that its inner end is forced against the 50 face of said clamp-plate. The outer end of said set screw is provided with a head or finger piece 28 for manipulating the same. Preferably said set screw extends diagonally downward through said front bar 18, so 55 that its end engages the clamp-plate obliquely, this position of the set screw serving best to hold the clamp-plate against upward vertical slip or vibration. The inner or clamping face of said clamp-plate 21 is 60 slightly concave from its upper to its lower portions, as indicated at 29 in Figure 3, and the lower or bottom edge 30 of said clamp-plate is slightly curved upwardly from end to end. This arrangement provides that as the clamping-plate 21 engages

the blade it will attain point contact therewith along its upper portion and at the corners of its lower portion, thus firmly holding the blade against slippage, and as the set screw forces the clamp-plate rearwardly against the blade, the inherent spring of the former will tend to flatten the same out so that under the pressure of the set screw all portions of the clamp-plate surface will be forced into close hugging and gripping relation to the blade, therefore rigidly holding the latter against all slippage, vibration or chattering, and assuring that its cutting edge will be so rigidly held in service, that lack of vibration or 80 chattering thereof, or of the blade body, will eliminate all "checking" of the surface scraped by said cutting edge, and will cause said cutting edge to produce a smooth, level and even shaving out of the surface 85 scraped.

The upper portion of the back plate 8 is reduced or diminished in width toward its upper end to provide a finger piece 31, and, in like manner, the upper portion of the clamp-plate 21 is reduced or diminished in width toward its upper end to provide a finger piece 32. The rear face of said clamp-plate finger piece 32, or that face thereof which is toward the blade, is forwardly and upwardly inclined or chamfered, as at 33. This arrangement serves a novel and valuable purpose, in that when it is desired to remove the blade, the set screw is loosened to retract its shank 27, thereupon by grasping the finger pieces 31 and 32 and squeezing the latter toward the former, the clamp-plate is rocked on the high point 34 at the base of the chamfered finger piece 32, so as to swing forwardly its main body 100 which provides its gripping portions, thus quickly and easily loosening the same from the blade 26, so that the latter may drop or be easily removed downwardly through the opening 2 of the base 1 and outwardly 110 from the holding frame, or as easily inserted upwardly through the opening 2 of the base 1 and into said holding frame.

From the above description it will be readily understood that my novel construction of blade holding frame, and particularly the novel construction and operation of the bodily and rearwardly movable clamp-plate, as guided in said frame, renders a highly efficient clamping function 120 adapted to firmly and rigidly engage a maximum portion of the blade body so that the same is most rigidly secured against slippage, vibration or chattering.

I am aware that some changes may be 125 made in the general arrangements and combinations of the several devices and parts of my present invention, as well as in the details of the construction of said parts, without departing from the scope of 130

my invention as set forth in the foregoing specification and as defined in the appended claims. Hence, I do not limit my invention to the exact arrangements and combinations 5 of the devices and parts as described in said specification, nor do I confine myself to the exact details of the construction of the said parts as illustrated in the accompanying drawings.

10 I claim:—

1. In a scraping tool, the combination with a base of a blade holder comprising a back plate, a transverse front bar provided with a clamp screw, end members 15 for rigidly connecting said front bar with said back plate in off-set relation thereto to provide an intermediate opening, a clamp-plate disposed in said opening intermediate said back plate and said front bar, 20 means for supporting said clamp plate for bodily movement toward said back-plate, a scraping blade disposed between said back-plate and said clamp-plate, and a transverse forwardly projecting guard flange adjacent 25 to the lower edge of said clamp-plate adapted to cover said opening intermediate

said clamp plate and said front bar, the same having an upwardly and forwardly chamfered under side.

2. In a scraping tool, the combination 30 with a base of a blade holder comprising a back plate, a transverse front bar rigidly associated with said back plate, a clamp plate intermediate said back plate and said front bar between which and said back plate 35 a blade is disposed, means for supporting said clamp-plate for bodily movement toward said back plate, the upper portion of said clamp-plate having an upwardly projecting finger piece provided with an upwardly and forwardly chamfered inner face 40 for purposes described, and a set screw passing through said front bar to engage and force said clamping plate rearwardly 45 into clamping position.

In testimony that I claim the invention set forth above I have hereunto set my hand this 22 day of December, 1919.

LEON NOVAK.
